HAT ADJUSTING MEANS

Sarah Lipton, New York, N. Y.; Jane Lipton
Orban administratrix of said Sarah Lipton,
deceased

Application February 15, 1944, Serial No. 522,437

4 Claims. (Cl. 132—59)

This invention relates to hats and to means for adjusting a hat to the head of the wearer.

In millinery shops a great variety of styles of hats must be carried, and since there are many different head sizes, the amount of stock which must be kept on hand is very large. The ordinary hat has no provision for adjustment to the head of the wearer so that between two standard sizes the customer is forced to elect the size which is nearest to a fit without securing an exact fit.

It has previously been proposed to provide various means for reducing the head size of a hat but these means have in general possessed the disadvantages that they must be sewn into the hat or stitched through the hat band, both of which operations are time consuming and, because of the nature of the retail trade in hats, often result in loss of sales which otherwise could be quickly consummated. Other prior constructions have been of a too bulky nature to justify their use on the hat band.

It is an object of the present invention to enable a hat to be quickly and conveniently modified, without alteration of the external appearance, so that it will snugly fit a head somewhat smaller than that for which it was designed, by securing adjusting means to two spaced points in the upper or free margin of the hat band and by providing a point or points of securing intermediate said spaced points, also in the hat band.

It is an object of the invention to provide a hat size adjuster which will cause contraction of the hat band to be distributed substantially equally between the two outer points of connection thereto.

This invention is an improvement upon the hat adjusting means covered in my previous Patent No. 2,092,808, and in Patent No. 2,325,473 issued jointly to myself and Ruby Lipton Brill.

In accordance with the present invention a cord is provided, preferably of elastic material, which has upon each end thereof an anchor pin and which has one or more intermediate stops thereon also in the form of an anchor pin or pins. The device may be formed of a single piece of cord having the anchor pin or pins secured at an intermediate point or points thereof, for instance by doubling the cord and clamping the anchor pin around the doubled cord, or otherwise securing the anchor pin or pins to the intermediate parts of the cord; or to the device may be made out of two pieces of cord, one or both of which may be elastic, and which pieces of cord are secured together by clamping the intermediate anchor pin

thereon. The device may be secured to the hatband by inserting the same through the hatband as described in my Patent No. 2,092,808, or it may be simply secured thereto by the end and intermediate pins similarly to the manner described in Patent No. 2,325,473. The present construction therefore combines the advantages of the constructions shown in both of said patents, and has the particular advantage over the construction shown in Patent 2,325,473 in that it requires less material and less labor to manufacture. The saving of material, particularly of elastic material, is especially important at the present time because of the shortage of such critical materials.

In the accompanying drawing,

Figure 1 is a front view of a hat looking into the crown thereof and showing the device secured to the hatband by means of the two end pins and the center pin.

Figure 2 is an elevation showing the adjusting device formed out of a single length of elastic having anchor pins on each end thereof and an anchor pin secured to a loop of the material at an intermediate point.

Figure 3 is an elevation of a modified form of adjuster in which the adjuster is made out of two pieces of material secured together by the center pin.

Figure 4 is an elevation of a modified form of adjuster provided with the intermediate pins.

Referring to the drawing in detail, the hat shown has a band 16 secured to the inside of the crown in the usual manner. The adjuster of the form shown in Figure 2 comprises a cord 20 preferably of elastic material which has an anchor pin 21 at each end thereof and which is looped or doubled at the center into a loop 23 around which is clamped an anchor pin 24. The anchor pins may be of any suitable construction, those illustrated each having a tubular body 25 which is clamped upon the cord, a point 27 at one end of the body, and a tail portion 28 at the other end of the body. The points 27 permit the pins to be pushed through the hatband after which the pin

body can be turned at an angle to the cord so that it engages behind the hatband permitting the cord to come out through the hole in the hatband through which the pin was inserted. The pin thus acts as an anchor.

In the form of the invention shown in Figure 3, the adjuster is formed of two cord portions 30, one or both of which may be of elastic. On the outer end of each of these cord portions is a pin 21, and the two adjacent ends of the cord portions are clamped within the body of the

center pin 24 so that the latter performs the functions of a stop and center anchor, as well as a means for securing the two cord portions together. As two separate cord portions are used in this construction, only one of them need be of elastic, thereby reducing the total amount of a critical material needed in the construction of the adjuster.

It is sometimes desirable to provide a hat adjuster which may be anchored to the hatband at more than one point between the end anchor pins. In this case an additional anchor pin or pins may be provided. Figure 4 shows an example of such a construction in which three intermediate anchor pins are provided.

It will be understood that the adjusters may be made of any desired length and that any suitable material may be used in their construction, and that any type of anchor pin may be employed.

While I have illustrated and described in detail certain preferred forms of my invention, it is to be understood that changes may be made therein and the invention embodied in other structures. I do not, therefore, desire to limit myself to the specific constructions illustrated, but intend to cover my invention broadly in whatever form its principle may be utilized.

What is claimed is:

1. A head size adjusting device for hats, having a flexible cord-like connecting element, an anchor pin clamped on each of the outer ends of the element, each of said anchor pins com-

prising a tubular body embracing the end of the flexible element and clamped in fixed engagement therewith and having point and tail portions extending from opposite ends of the body, and an anchor pin having a tubular body embracing and clamped to two adjacent cord portions intermediate the length of the flexible element, said anchor pin having point and tail portions extending from opposite ends of the body.

5 2. A head size adjusting device for hats as claimed in claim 1 in which the flexible element comprises a single piece extending from one end pin to the other end pin, and doubled at an intermediate point for attachment of an intermediate anchor pin, both parts of the doubled portion being embraced by the body portion of said intermediate pin.

10 3. A head size adjusting device as claimed in claim 1 in which the flexible element is formed of two pieces, each extending from an outer anchor pin to the center anchor pin, the two adjacent ends of said cord portions being embraced and clamped together by said center anchor pin.

15 4. A head size adjusting device for hats as claimed in claim 1, comprising a flexible connecting element, anchor pins at each end thereof, and a plurality of spaced anchor pins attached to the flexible element at intermediate points thereof.

SARAH LIPTON.
